TRIMMING BOARD

Robert A. Webster, Santa Monica, Calif.

Application April 26, 1945, Serial No. 590,340

10 Claims. (Cl. 164—59)

1 This invention constitutes an improvement in trimming boards and in adjustable guides therefor.

The trimming boards with which the invention is concerned are used generally in cutting pieces of paper, film, or other thin sheet material down to smaller desired sizes. One of the principal uses of such boards is in dividing or trimming the edges of sheets of sensitized paper for use in photographic printing. Although the boards now known and generally used are provided with ruler scales and other markings to assist in predetermining the size of the cut sheet they are very difficult to use because the cutting must be done in complete darkness or in the presence of a "safe" light. The latter gives off a very dull red glow which is of very little use in attempting to locate the dimensional markings on the board.

In using present day trimming boards, which have a shearing device along one edge and a scale along another side at right angles to the first, for cutting light sensitive sheets to new sizes it is necessary to determine the dimensions in ordinary light and then insert pins or tacks in the board or attach pieces of tape to it to serve as locating points. The distance from these points to the shearing edge determines the finished size of the paper. Such arrangements are obviously clumsy and uncertain. When the board is used in partial or complete darkness it is very difficult to line the sheet up accurately with the locating points. Moreover, it is usually desired to cut the paper to a rectangular shape of greater length than width and the pins or tacks determining the shorter dimension are, of course, in the way when it is desired to cut the longer dimension.

The novel features of my invention completely obviate the difficulties mentioned above by providing a plurality of separate stops or guides which may be fixedly located at any desired points to predetermine the dimensions of the sheet to be cut and which may be moved to non-interfering positions without affecting their adjustment.

Another defect of conventional trimming boards resides in their basic construction in which a separate ruler is laid on the surface of the board along one edge and attached with screws or other fastening means. The inner edge of the ruler is then used to square the paper with the cutting edge. In practice, the ruler frequently becomes warped or the fastening means become loose, with the result that the paper can slip under the edge of the ruler without being observed in the darkness and a square cut is not obtained.

Another novel feature of my invention is the provision of means to block off the opening between the ruler and the board or to eliminate the opening entirely by modification of the construction of the ruler.

2 A principal object of my invention is to provide easily operated adjustable stop means to locate paper or other thin sheet material on a trimming board for the purpose of cutting it to a desired size.

A further object is to provide a plurality of independent adjustable stop means which may be used in conjunction with each other but without mutual interference.

An additional object is to provide stop means which may be initially adjusted to desired positions and may be subsequently operated accurately regardless of visibility.

Another object is to provide novel means on a trimming board to positively guide one edge of a thin sheet of material at right angles to the cutting edge of the board.

Other and further objects will become apparent as the description proceeds.

20 The preferred form of my invention is illustrated in the accompanying drawing in which:

Fig. 1 is a perspective view of a trimming board showing certain features of the invention;

Fig. 2 is a sectional view taken along line 2—2 of Fig. 1;

Fig. 3 is a top plan view of the structure shown in Fig. 2;

Fig. 4 is a view similar to Fig. 2 showing a modified form of stop means;

Fig. 5 is a top plan view of the structure shown in Fig. 4;

Fig. 6 is an end view of a portion of a trimming board showing another feature of my invention; and

Fig. 7 is a view similar to Fig. 6 showing a further modification.

The trimming board, generally indicated at 10 in Fig. 1, has a level upper surface or bed plate 11 and is provided with the usual inset metal edge plate 12, which cooperates with knife 14 to shear paper or other sheet material. The knife is pivotally carried in conventional manner by a support 16 attached to a rear corner of the board. A ruler or scale 18 is mounted along the rear edge of the board to guide and align the paper and to serve as measuring means. The board itself is mounted on a pair of foundation strips 20.

A support rail 22, carried by pedestals 24, is mounted in a position spaced above and parallel to the longitudinal axis of the scale. The rail is preferably square in cross section. Two or more adjustable stop members 26 are slidably carried on the rail for adjustment to any desired position along its length.

As shown in detail in Figs. 2 and 3, each stop member is composed of a section of round bar thru which a square bore or passageway 28 is formed to adapt it to slide on rail 22 without rotation. A small screw 30 with a knurled head 60 is threaded into a wall of the stop member for

3

binding engagement with the rail to secure the stop member firmly in any selected position. A circular boss of reduced diameter is provided adjacent one end of said member and the arm 32 is pivotally mounted thereon. The extreme end of the boss is headed over, as at 34, to retain the arm. A vertical extension of the arm forms a foot 36 for contact with the surface of the board to serve as a dimensional guide for the paper to be cut.

It is essential that the foot be maintained in firm contact with the board when in operative position so that the paper cannot slip past it. This is assured by the use of an over-center spring device. A small hole 38 is bored partially thru the wall of member 26 and a corresponding hole 40 is bored thru depending lip 42 which is integral with the arm 32. A pin 44 bottoms in hole 38 and passes thru hole 40 and is provided with a collar 46 intermediate its ends. A spring 48, of sufficient free length to be substantially compressed, is slipped over the pin between collar 46 and lip 42 and tends to constantly urge the lip away from the base of hole 38.

Since the base of the hole is not coaxial with the pivot of arm 32 the spring may elongate at each side of a center position and therefore urges the arm 32 up or down from neutral position, depending on the position to which the arm has been moved manually. Thus it tends to hold the foot 36 down in contact with the surface of the board when swung below center and holds the foot up out of the way when swung above center.

The two stop members are substantially identical in construction but are made right and left hand, as indicated in Fig. 1, so that the feet 36 may be set very close together if it is desired to cut a sheet having almost identical dimensions in width and length.

The type of stop member above described is particularly suitable for use in an attachment to be applied to trimming boards which are already in use because of the necessity for maintaining firm contact between the foot and the level surface of the board. However, in the case of new boards, a still further improvement is available. As seen in Fig. 2, this consists of a shallow depression 48' formed in the upper surface of the bed plate adjacent and parallel to the scale 18. While this depression may be of any shape, it is preferably arcuate in cross section as shown. It will be readily seen that the foot 36, when in contact with the bottom of the depression, is well below the surface or bed plate 11 of the board and consequently the thinnest sheet of material cannot be accidentally slipped beneath it.

When a trimming board is provided with such a depression or groove it is possible to use a simpler type of stop or guide with equal satisfaction. Such a guide is shown in Figs. 4 and 5 in which the stop member 50 is made from a piece of strap metal bent to V-shape and provided with a pair of square apertures 52 to engage and slide on Rail 22. A set screw 54 is threaded thru the base of the stop member 50 to bindingly engage the support rail and hold the stop firmly in adjusted position. Arm 56 is pivotally attached to stop member 50 by a pin 58 which may be a rivet or a bolt and nut. A spring washer 60 is arranged to urge the arm 56 into frictional engagement with the stop member 50 to assist in retaining the arm in any position to which it

is manually swung. Foot 62, which is integral with arm 56, is adapted to engage the bottom of the depression or groove 48'.

With either of the constructions described in detail above it will be obvious that each stop may be adjusted exactly to a position in which it will determine one of the dimensions to which a sheet is to be cut and secured in that position for subsequent operations. The feet may then be swung down into contact with the board and a sheet of paper placed thereon with one edge in contact with the scale and another edge in contact with the stop determining the shorter dimension. After the cut is made, the foot nearest to the cutting edge may be raised to a noninterfering position. The sheet may be again placed on the board with its long edge against the scale and one end against the remaining stop. The second cut is then made and the sheet is completed with its edges squared and its dimensions exactly as desired. The original settings can be made in ordinary light and the work can then be done in total darkness since there is no possibility of the stops slipping or of the operator being unable to locate the sheet properly.

Fig. 6 illustrates another important feature of my invention. It has been found in practice that no matter how tightly scale 18 is attached to the board 10, it eventually loosens or warps sufficiently to allow some clearance between the scale and the surface 11, as illustrated in exaggerated form at 62. As a consequence, the edge of the sheet to be cut frequently slips under the scale and is not properly trued up with the cutting edge, resulting in inaccurate cutting and waste. The solution to this problem is the provision of strip 64, located in channel 66 and extending immediately adjacent and along the entire length of scale 18. Since the vertical edge 61, forming a guide face, extends vertically above and below surface 11, it will be apparent that any sheet laid on the surface can be trued up without any possibility of error.

Fig. 7 shows a modification in which scale 68 is provided with an integral depending flange 70 seated in channel 72 to provide a vertical guide face 73 extending above and below surface 11 to serve the same purpose as the construction of Fig. 6. This is a particularly suitable design for construction from an angle shaped strip of extruded metal.

It will be apparent that the combination of novel features described hereinabove provides a simple, convenient, and highly practical trimming board which is suitable for general use and is especially valuable for work in a photographic darkroom, where it eliminates any possibility of error in the locating and dimensioning of sheets to be cut. It is also highly advantageous in ordinary light because the use of a mechanical stop gives absolute uniformity of dimension where a number of sheets are to be cut to the same size. Such uniformity cannot be obtained with the present practice of separate visual alignment of each sheet.

While I have shown the preferred embodiment of the invention in the accompanying drawing it will be obvious that various modifications may be made without departing from its spirit or scope and it is intended to embrace all such modifications in the following claims.

I claim:

1. In combination with a trimming board having a planar, imperforate bed plate provided with a means along one edge for shearing a thin sheet

of material: guide means extending along another edge of said bed plate for substantially the entire length of said edge for aligning a thin sheet of material; a support member mounted adjacent and parallel to said guide means and extending along substantially the entire length of said last mentioned edge; and a pair of stop means slidably mounted on said support member for longitudinal movement along substantially its entire length parallel to said guide means and toward and away from said shearing means, said stop means further being mounted for substantially vertical movement to positions spaced above and in contact with the surface of said bed plate.

2. The construction claimed in claim 1; in which said stop means is provided with means to secure it in any desired position of longitudinal adjustment.

3. The construction claimed in claim 1; in which each of said stop means comprises a first part movable only in a horizontal plane spaced above and parallel to the surface of said bed plate, and a second part pivotally mounted on said first part for movement in a vertical plane normal to the surface of said bed plate.

4. In combination with a trimming board having a substantially planar, imperforate bed plate provided with means along substantially the entire length of one edge for shearing thin sheets of material: guide means extending along substantially the entire length of another edge of said bed plate for aligning a thin sheet of material; support means extending parallel and adjacent to said guide means and along substantially the entire length of said last mentioned edge; and a plurality of stop means independently slidably mounted on said support means for movement therealong and serving to determine the principal dimensions of a sheet to be trimmed; at least one of said stop means being adapted to be moved into juxtaposition with the surface of said bed plate and to be raised to a position spaced substantially thereabove.

5. The construction claimed in claim 4; in which at least one of said stop means comprises a first part slidably mounted on said support means and a second part pivotally mounted on said first part for vertical movement.

6. An attachment for a trimming board having shearing means along one edge and guide means along another edge, comprising: a longitudinally extending support rail of non-circular cross-section adapted to be attached to said board adjacent to said guide means; and a plurality of dimension determining stop members slidably and non-rotatably mounted on said support rail for movement therealong to any desired position; a foot pivotally mounted on at least one of said stop members for movement in a plane normal to the longitudinal axis of said support rail; and over-center spring means mounted between said stop member and said foot to urge said foot toward positions angularly displaced from a predetermined neutral position.

7. An attachment for a trimming board having shearing means along one edge and guide means along another edge, comprising: a longitudinally extending support rail of non-circular cross-section adapted to be attached to said board adjacent to said guide means; and a plurality of dimension determining stop members slidably and non-rotatably mounted on said support rail

for movement therealong to any desired position; a foot pivotally mounted on at least one of said stop members for movement in a plane normal to the longitudinal axis of said support rail; and resilient friction producing means combined with the pivotal mounting of said foot tending to retain said foot in any position of angular adjustment to which it may be set.

8. In combination with a trimming board having a bed plate provided with means along one edge for shearing thin sheets of material: guide means extending along another edge of said bed plate for aligning a thin sheet of material; said guide means comprising a substantially flat, longitudinally extending strip provided with a downwardly extending flange; said bed plate being provided with a channel in its surface co-extensive with said flange; said strip lying directly in contact with the surface of said bed plate and said flange extending downwardly into said channel.

9. In combination with a trimming board having a bed plate provided with means along one edge for shearing sheets of material: guide means extending along another edge of said bed plate for aligning a sheet of material; stop means mounted for longitudinal movement parallel to said guide means and toward and away from said shearing means; and a depression in the upper surface of said bed plate extending parallel to said guide means and in the path of the lower edge of said stop means.

10. In combination with a trimming board having a planar, imperforate bed plate provided with means along one edge for shearing a thin sheet of material: guide means extending along another edge of said bed plate for substantially the entire length of said edge for aligning a thin sheet of material; a support member mounted adjacent and parallel to said guide means and extending along substantially the entire length of said last mentioned edge; and a pair of stop means slidably mounted on said support member for longitudinal movement along substantially its entire length parallel to said guide means and toward and away from said shearing means, said stop means further being mounted for substantially vertical movement to positions spaced above and in contact with the surface of said bed plate; said bed plate being provided with a depression in its upper surface extending parallel to said guide means and in the path of vertical movement of said stop means, whereby the lower edge of said stop means may be positioned in said depression below the normal surface of said bed plate.
